UNITED STATES PATENT OFFICE.

EDWIN N. PREBLE, OF BEVERLY, MASSACHUSETTS, ASSIGNOR TO UNITED SHOE MACHINERY COMPANY, OF PATERSON, NEW JERSEY, A CORPORATION OF NEW JERSEY.

GAGE MECHANISM FOR SOLE-PRESSING MACHINES.

1,221,214.

Specification of Letters Patent.

Patented Apr. 3, 1917.

Application filed August 2, 1915. Serial No. 43,309.

To all whom it may concern:

Be it known that I, EDWIN N. PREBLE, a citizen of the United States, residing at Beverly, in the county of Essex and State 5 of Massachusetts, have invented certain new and useful Improvements in Gage Mechanism for Sole-Pressing Machines; and I do hereby declare the following to be a full, clear, and exact description of the invention, 10 such as will enable others skilled in the art to which it appertains to make and use the same.

The present invention relates to sole pressing machines, and more particularly to 15 mechanism for gaging the position of a flat sole with relation to the coöperating pressing forms.

The object of the present invention is to 20 provide an improved type of gaging mechanism which coöperates with the sole supporting form to locate the flat sole in proper operative relation to the pressing form. With the above object in view, the several 25 features of the invention consist in certain novel features of construction and combinations and arrangement of parts hereinafter described and claimed, the advantages of which will be obvious to those skilled in the art from the following description.

30 In the accompanying drawings illustrating the preferred form of the invention, Figure 1 represents an elevation, partly in section, of the supporting forms and coöperating gage devices, and Fig. 2 is a view 35 illustrating the gage devices with the forms removed from operative relation thereto.

The present invention is illustrated in 40 connection with a machine of the type shown and described in the patent to Preble, No. 1,004,075, dated September 26, 1911. This machine comprises a sole supporting form 1 and a coöperating pressing form 2 which are relatively actuated to press a flat sole, indicated at 3, between them. The sole 45 supporting form is mounted upon a horizontally movable slide 5 which is actuated in the usual manner, and is provided with a carrier 7 supporting a gripping device 8 and heel gage 9. The heel gage comprises 50 a pair of oppositely extending wings 10 which are pivoted at 11 upon a gage block 12 in such a manner that the heel end of the

sole is allowed to extend between the wings to position the sole longitudinally and center it with relation to the supporting form. 55

It is desirable that the wings of the gage member shall permanently contact with the surface of the sole supporting form independently of the height of the form, in order to maintain the gage member in operative 60 relation to the heel end of the sole and to prevent the insertion of the sole between the wings of the gage and the surface of the form. To this end the present invention contemplates the provision of a heel gage 65 which is pivoted at one end and is provided with means for yieldingly maintaining the wings of the gage member in contact with the surface of the sole supporting form which extends beneath the gage, the rear 70 end being indicated in dotted lines in Fig. 1. The gage block is fulcrumed at 15 upon a gage slide 16 which is adjustably mounted in the usual manner upon a guide rod 17 forming a part of the carrier 7. The rear 75 end of the gage block is provided with a depending tail 19 which is engaged by a plunger 20 slidingly supported in the slide 16 and actuated by a spring 22 to normally maintain the wings of the gage member in 80 contact with the surface of the form. With this construction, it will be noted that the position of the heel gage may be conveniently adjusted by moving the slide 16, and the wings of the gage member are permanently maintained in contact with the surface of the form through the action of the spring-pressed plunger which contacts with the depending tail 19.

While it is preferred to employ the specific construction and arrangement of parts shown and described, it will be understood that this construction and arrangement is not essential except so far as specified in the claims, and may be changed or modified 95 without departing from the broader features of the invention.

The invention having been described, what is claimed is:—

1. A sole pressing machine comprising coöperating sole pressing forms, an adjustable gage slide, a heel gage fulcrumed upon the slide and projecting over the surface of the sole supporting form, and means for main-

2
taining the gage in yielding contact with the surface of the form.

2. A sole pressing machine comprising co-operating sole pressing forms, a gage slide adjustable with relation to the forms, a heel gage fulcrumed upon the slide and having

a depending tail, and a spring-pressed plunger mounted in the slide and engaging with the tail to normally maintain the gage in contact with the surface of the sole supporting form. 10

EDWIN N. PREBLE.
